UNITED STATES PATENT OFFICE.

CHARLES T. BOARDMAN, OF BERGEN POINT, NEW JERSEY.

IMPROVEMENT IN HEATERS.

Specification forming part of Letters Patent No. 42,161, dated April 5, 1864.

To all whom it may concern:

Be it known that I, CHARLES T. BOARDMAN, of Bergen Point, in the county of Hudson and State of New Jersey, have invented a new and useful Improvement in Steam-Heating Apparatus; and I do hereby declare that the following is a full, clear, and exact description of the same, reference being had to the accompanying drawings, forming part of this specification, in which—

Figure 1 is a central vertical section of the apparatus. Fig. 2 is a horizontal section of the same in the plane indicated by the line $x-x$ in Fig. 1. Fig. 3 is a horizontal section of the same in the plane indicated by the line $y-y$ in Fig. 1.

Similar letters of reference indicate corresponding parts in the several figures.

The first part of my invention relates to tubular radiators applied upon or in connection with steam-boilers for heating and for the supply of buildings or apartments; and it consists in a certain arrangement of deflectors, in combination with an upright series of steam-tubes, an upper steam-chamber, and a surrounding air-casing, for the purpose of conducting the air to be heated among the said tubes and in contact with the whole of the surface of the said upper chamber.

The second part of my invention consists in a certain arrangement of the flue of a boiler for steam heating, in combination with an air-casing surrounding the boiler and indicator, whereby the heat of the escaping gaseous products of combustion is economized by using it partly to heat the boiler and partly to heat the air for the supply of the building or apartment.

To enable others skilled in the art to make and use my invention, I will proceed to describe its construction and operation.

A is an upright plain cylinder-boiler, having arranged within it a fire-box, B, and surrounded entirely with an annular flue, C, into the upper part of which the gaseous products of combustion pass from the upper part of the fire-box by means of two or more short horizontal passages, $a-a$, and from the lower part of which the said products pass through a passage, b , to the chimney. The boiler is filled with water to a suitable height above the

crown-plate c of the fire-box to prevent the said plate from burning, and its upper part, d , serves as steam-space.

D are a series of upright steam-tubes, and E a steam-chamber above them. These tubes and chamber constitute the radiator. The said tubes are arranged at suitable distances apart all over the tube-sheet e , which forms the top of the boiler, and serve to convey the steam into the upper chamber, E, in the bottom of which their upper ends are secured. This upper steam-chamber, E, is of a circular form in its horizontal section of a circumference about equal to or rather larger than that of the boiler.

F is an upright cylindrical casing of larger diameter than the flue C and chamber E, enclosing the whole of the boiler and radiator, having openings $f-f$ around the lower part and openings $g-g$ at some distance above the boiler for the admission of fresh air to be heated and supplied to the building or apartment, and an opening, h , at the top for the connection of a pipe to convey the heated air to the building or apartment.

i is a horizontal annular deflecting-plate arranged within and fitted to the interior of the casing F just below the openings $g-g$ and extending inward among the tubes D D.

j is another horizontal annular deflecting-plate arranged within and fitted to the interior of the casing F above the openings $g-g$ and extending inward as far as the exteriors of the outermost tubes D D.

k is an upright hollow cylinder, open at the top and bottom, closely surrounding the outermost tubes D D, and connected at its lower edge with the inner edge of the plate j .

The apparatus described is intended to be placed in the basement or lower part of a building into which fresh cool air is copiously admitted, and this air enters the apparatus through the openings $f-f$ and $g-g$. The air entering at $g-g$ below the deflecting-plate or deflector j is distributed among the whole of the tubes D D, instead of only among the outermost ones, as it would otherwise be, and is confined among the said tubes as it circulates upward by the deflecting-cylinder or deflector k , and so caused to pass in contact with the whole surface of the bottom of the chamber E of the

diator, whence it passes outward over the sides of the said chamber and over the top thereof before passing to the opening *h*. The air entering at *ff* passes upward between the boiler *F* and the exterior surface of the flue *C*, and is heated by contact with the latter surface, and is afterward caused by the deflecting-plate or deflector *i* to pass over the top of the boiler and among the tubes *D D*, whence it passes under, around, and over the chamber *E*, and is further heated in the same manner as the air entering at *gg*, before passing off at *h*. The radiator constructed as described, surrounded by a casing, *F*, and deflectors *i j k*, may be arranged at a distance from the boiler and supplied with steam by a suitable pipe.

What I claim as my invention, and desire to secure by Letters Patent, is—

1. The combination of the horizontal deflectors *j* and vertical deflectors *k* with the boiler *A*, annular flue *C*, and deflector *D E*, constructed, arranged, and operating as described.
2. The combination, with each other and with the boiler *A* and radiator *D D F*, of the annular flue *C*, casing *F*, and deflector *i*, substantially as and for the purpose herein set forth.

C. T. BOARDMAN.
